UNITED STATES PATENT OFFICE.

DANIEL W. McCCLURE AND HAROLD HARRIS, OF WOODLAWN, PENNSYLVANIA.

POLISHING DEVICE.

Application filed July 25, 1923. Serial No. 653,642.

To all whom it may concern:

Be it known that we, DANIEL W. McCCLURE and HAROLD HARRIS, citizens of the United States, residing at Woodlawn, in the county of Beaver and State of Pennsylvania, have invented certain new and useful Improvements in Polishing Devices, of which the following is a specification.

This invention relates to polishing devices particularly adapted for polishing sheet and tin plate finishing rolls for the purpose of eliminating roughness on the surface of the finished tin plate and the surface of the rolls.

More specifically the invention relates to a sectional polishing apparatus to eliminate the rough surface of the bottom rolls in tin-plate and finishing mills; to remove rough surfaces from the rolls while in operation without interfering with production; and to polish the bottom roll, at will, at whatever point on the roll the roughness occurs.

An object of the invention is to produce a device of the above kind which embraces the desired qualities of simplicity, durability and efficiency in operation.

Other objects will appear as the nature of the invention is better understood, and the same consists in the novel form, combination and arrangement of parts hereinafter more fully described, shown in the accompanying drawing and claimed.

In the drawings, wherein like reference characters indicate corresponding parts throughout the several views,

Figure 1 is an elevational view of a finishing machine with a polishing device constructed in accordance with the present invention, associated with the lower roll thereof.

Figure 2 is an enlarged fragmentary longitudinal sectional view of the polishing device per se.

Figure 3 is a transverse sectional view taken substantially upon line 3-3 of Figure 2.

Figure 4 is an enlarged perspective view of one of the stoneholders.

Figure 5 is a view similar to Figure 4 of one of the springs employed for yieldingly urging the stones into contact with the roll.

Figure 6 is a perspective view of the bar which carries the adjusting screws, and

Figure 7 is a perspective view of one of the stones.

Referring more in detail to the drawing, the present invention is adapted to be applied to tin plate and finishing mills embodying superimposed rolls 5 and 6 suitably journaled in uprights 7 and between which the tin plate is passed when being finished.

It is found that roughness often occurs with respect to the surface of the lower roll 5 and that this roughness is imparted to the plates if not eliminated. Oftentimes the roughness occurs only at isolated points on the roll, although sometimes this roughness occurs entirely from end to end of the roll. Obviously, when the roughness occurs in spots or isolated places on the periphery of the roll it is undesirable and unnecessary to polish the entire surface of the roll.

The device constituting the present invention enables the roll to be polished from end to end if necessary, and at the same time has provision for polishing any desired part of the roll if found desirable. As shown, the device embodies a supporting channel 8 which is of a length substantially corresponding to the length of the roll 5 and which has its bottom wall rigidly secured upon a mounting bracket 9 by means of bolts 10 or the like, the bracket 9 being in the form of a strip of rigid metal with downturned ends secured as at 11 to the standards 7 whereby the channel 8 is rigidly mounted longitudinally of the roll and beneath the latter as shown in Figure 1.

Disposed within the channel member 8 is a bar 12 which is provided with a plurality of screw threaded openings 13 in which the adjusting screws 14 have threaded engagement, said screws being loosely extended through aligned openings in the channel 8 and the bracket 9 as indicated at 15 in Figure 2.

The polishing element embodies a plurality of stones 16 arranged in end to end relation and whose combined lengths is suitably equal to the length of the roll 5, and each stone is disposed within a separate channel-shape holder 17. The holders 17 are thus disposed in end to end spaced relation, as shown in Figure 1, and are of such length as to each be engaged by a pair of the adjusting screws 14, one screw being associated with each end of each holder. It is thus apparent that the several stones are individually adjustable vertically into or out of contact with the adjacent portions of the

the surface of the roll 5, the holders 17 being vertically slidable in and guided between the flanges of the supporting channel 8.

In order to insure a yielding contact of the stones with the surface of the roll 5 for insuring uniform pressure against the latter, springs are interposed between the bottoms of the holders 17 and the stones 16. Each spring is preferably of the form shown in Figures 2 and 5 embodying a pair of oppositely curved leaf spring members 18 centrally secured together as at 19 and having their separated ends respectively engaging the ends of the holder and the stone.

If the bottom roll 5 is found to be rough from one end to the other, it can be kept clean and polished entirely across the same by adjusting the screws 14 to place the same pressure on all of the stones 16 with the latter yieldingly engaging the surface of the roll. On the other hand in case a roughness only occurs at isolated points the desired stones may be independently adjusted into contact with the surface of the roll under the necessary pressure, the remaining stones being left out of contact with the roll at this time.

From the above description, it is believed

that the construction and operation, as well as the advantages of the present invention, will be readily understood and appreciated by those skilled in the art.

Minor changes may be made without departing from the spirit and scope of the invention as claimed.

What we claim as new is:

A polishing device comprising a bar, adjusting screws threaded through the bar, a U-shaped guide member receiving the bar, set screws passing through the intermediate portion of said guide member, a U-shaped holder member movably mounted between the sides of the guide member and bearing at its intermediate portion against the ends of the set screws, longitudinally curved leaf springs convexed toward each other and secured together at points between their ends, the ends of one of the leaf springs bearing upon the intermediate portion of the holder in the vicinity of the ends thereof and a polishing stone received between the sides of the holder and bearing at its ends upon the ends of the other leaf spring.

In testimony whereof we affix our signatures.

DANIEL W. MCCLURIN.
HAROLD HARRIS.
